UNITED STATES PATENT OFFICE.

JOSEPH L. KOST, OF GALVESTON, TEXAS, ASSIGNOR OF ONE-HALF TO JAMES H. SHIVELY,
OF GALVESTON, TEXAS.

MAIL-BAG-DELIVERING APPARATUS.

1,266,824.

Specification of Letters Patent. Patented May 21, 1918.

Application filed August 31, 1917. Serial No. 189,138.

To all whom it may concern:

Be it known that I, JOSEPH L. KOST, a citizen of the United States, residing at Galveston, in the county of Galveston, State of Texas, have invented certain new and useful Improvements in Mail-Bag-Delivering Apparatus, of which the following is a description, reference being had to the accompanying drawing and to the figures of reference marked thereon.

My invention relates to a device for effecting the receipt of bags and the like from and the delivery thereof to railway trains, cars, etc., while the latter are in motion.

It contemplates a combination of supporting devices upon the car or vehicle and at the station or fixed point of receipt and delivery which will be simple, economical in construction and highly efficient in operation. Its further purposes are that both receipt and delivery of bags and the like shall be effected with the highest degree of security to the contents thereof, and that the device shall be moved out of operative position immediately on receipt of a bag, this being effected by the impact of the bag itself. Further objects will be apparent from the description hereinafter contained.

In order to illustrate my invention I have shown an embodiment thereof in the accompanying drawings, wherein—

Figure 1 is a side elevation of my device, showing the moving railway car partially broken away.

Fig. 2 is a plan view of the receiving and delivering device at the station and

Fig. 3 is a perspective view of the bag support and catcher attached to the car.

In the drawings 5 represents a moving car, 40 in the door 6 of which is fitted a frame 7, suitably of metal, and pivoted at opposite sides of the door frame at 8, 8 by means of pins 9, 9. This frame, in inoperative position, fits closely but freely within the door of the car, and thus forms no obstruction to entrance or egress therefrom. It is provided at its lower end with a handle 10, whereby it may be moved about its pivots 9, and at its upper end with a bag support 11, pivotally hung at 12 between L-plates 13 securely bolted or otherwise fixed to the top bar of frame 7, and having upwardly turned, hooked ends 14, 14, facing in opposite directions. In operation the bag 15 to be de-

livered from the car to the station is hung 55 on the hooked end 14 which is pointed in the direction opposite that in which the car moves, and the other hook 14 picks up the bag from the support and receiver at the station.

The station support and receiver comprises two horizontal, spaced parallel bars or rails 16, 16 which are attached by suitable supporting plates 17, 17 to a rotatable post 18. In one direction from said post the 65 spaced, parallel rails 16, 16 extend horizontally for equal distances, forming the horizontal receiving portion 19, 19; are then inclined downwardly, this inclined receiving portion being indicated as 20, 20 and are 70 then caused to converge to a point 21. In the opposite direction the rails extend equal distances from said post and are then cut off, forming the horizontal delivery portion 22.

The supporting post 18 is rotatably mounted in a bearing collar 23 and thrust plate 24 carried by a movable car or truck 25 mounted on wheels 26 which are guided in suitable channel irons 27 positioned at right angles 80 to the track on which the railway car moves. The post, together with the supporting and receiving device carried by it, is thus capable of movement toward and away from the track on which the car 5 operates as well as 85 of a rotary movement about the axis of the post.

In the embodiment illustrated the bags 15 are shown as provided with a metallic frame 28 to which the chain 29 is attached at opposite sides of the bag.

In operation the bag to be removed from the car is hung by the chain 29 on the hook 14 of the bag support 11 facing in the direction opposite that in which the car is moving, which is indicated by an arrow. The station support is moved near the track on which the car moves and is rotated so that it is parallel thereto with the converging end 21 pointing in the direction from which the car comes. As the car with the bag approaches, the operator within the car tilts the frame 7 so that the converging end 21 of the station support will enter the loop of chain 29 and the bag support 11 pass between rails 16. The impetus of the bag causes it to slide along the receiving member, ascending the inclined portion 20 the chain 29

impacting against suitable shock absorbers attached to the horizontal section 19. These shock absorbers, in the embodiment shown, consist of rods 31 provided with heads 32 and mounted in bearings 33, 33 so as to be capable of reciprocal movement. They are provided with coiled springs 34 which engage at one end with one of the bearings 33 and at the other end against collars 35 fixed 10 to rods 31, and which offer resistance to the movement of the impacting bags and absorb the shock of their impact.

If a bag is to be picked up by the moving car it is suspended by its chain 29 over 15 the horizontal delivery portion 22. The forward hooked end 14 of the bag support 11, passing between these bars, engages the chain and removes the bag. A curved guide member 36 is provided, below which the bag 20 is suspended, and which prevents the bag from being thrown upwardly in its movement. The station receiver and support is caused to move away from the car track by the impact of the bag in the following manner. A cable or rope 37 is attached to a suitable eye 38 fixed to the truck 25, passes over a sheave 39 mounted on a post 40 and then over a sheave 41 mounted on a post 42 arranged at a distance from post 18 in the 25 direction of the receiving end 21 of the station receiver. Rope 37 terminates in a hook 43, which is engaged in eye 44 attached to the end of a rope hammock 45 suspended from the bars 16, 16, preferably to the rear 30 of shock absorbers 31, 31.

The operation of the above described device is as follows:

When a bag is caught by the station receiver its inertia drives it along rails 16 40 until stopped by the shock absorbers, the lower end of the bag striking heavily against the hammock. This results in a pull on rope 37, which causes movement of the truck away from the car track.

45 When the car is moving in the direction opposite that shown the station receiving and delivering device is rotated about post 18 through an angle of 180°, the devices again having the same relative position and co-operation shown. It is obvious that a second rope and set of sheaves corresponding to that shown may be provided on the opposite side for effecting the lateral movement of the device, the eye 44 of the hammock 45 being engaged by the hook of said rope.

Having described the above embodiment of my invention, I claim:

1. In a device of the class described, a 60 station receiving and delivering member comprising a support, spaced horizontal rails carried by said support, said rails being inclined downwardly and converging to a point at one end, whereby they are capable 65 of entering the loop of a bag, and said rails

being cut off at points equidistant from the support at the other end.

2. In a device of the class described, a station receiving and delivering member comprising a rotatable support, spaced horizontal rails carried by said support, said rails being inclined downwardly and converging to a point at one end, whereby they are capable of entering the loop of a bag, shock absorbers mounted on said rails, and said rails being cut off at points equidistant from the support at the other end. 70 75

3. In a device of the class described, a station receiving and delivering member comprising a rotatable support, spaced, horizontal rails carried by said support, said rails being inclined downwardly and converging to a point at one end, thereby forming a bag receiving end, said rails being continued beyond the support at the opposite end, a laterally movable truck for carrying the rotatable support, and means for moving said truck actuated by the impact of delivery to said receiving and delivering member. 80 85

4. In a device of the class described, a station receiving and delivering member comprising a rotatable support, spaced, horizontal rails carried by said support, said rails being inclined downwardly and converging to a point at one end, thereby forming a bag receiving end, said rails being continued beyond the support at the opposite end, a laterally movable truck for carrying the rotatable support, means for moving said truck, said means comprising a rope attached to the truck, guiding means for said rope, and a hammock suspended from the receiving and delivering member below the receiving end thereof and attached to said rope, whereby impact upon said hammock causes a pull on said rope. 90 95

5. In a device of the class described, a station receiving and delivering member comprising a rotatable support, spaced, horizontal rails carried by said support, said rails being inclined downwardly and converging to a point at one end thereby forming a bag receiving end, said rails being continued beyond the support at the opposite end to form a bag delivering end, and a curved guide below said delivering end for limiting upward movement of bags delivered thereby. 100 105 110

6. In a device of the class described, 115 means for supporting a bag carried by a moving car, said supporting means comprising a frame pivotally mounted in the door of the car, a support pivotally hung to the top of said frame, said support comprising hook-like members facing in opposite directions, a station receiving and delivering member comprising spaced receiving and delivering rails, and means for moving the frame of the bag supporting means to 120 125 130

cause the support mounted thereon to pass between the rails of the station receiving and delivering member.

7. In a device of the class described, a station receiving and delivering member comprising a rotatable support, receiving and delivery means carried by said support, a laterally movable carrier for said support, and means actuated by the impact of deliv-

ery to said receiving means for moving said 10 truck.

In testimony whereof, I affix my signature, in the presence of two witnesses.
